UNITED STATES PATENT OFFICE

EMIL METZGER, OF WEEHAWKEN, NEW JERSEY, ASSIGNOR TO HEATHER HANDKERCHIEF WORKS, OF JERSEY CITY, NEW JERSEY, A CORPORATION OF NEW YORK

DESIGN FOR A HANDKERCHIEF OR SIMILAR ARTICLE

Application filed October 1, 1932. Serial No. 45,191. Term of patent 14 years.

To all whom it may concern:

Be it known that EMIL METZGER, a citizen of the United States, and resident of Weehawken, in the county of Hudson and State of New Jersey, has invented a new, original, and ornamental Design for Handkerchief or Similar Article, of which the following is a specification, reference being had to the accompanying drawing, forming part thereof, in which—

Fig. 1 is a plan view of a handkerchief embodying my new design; and

Fig. 2 is a cross-sectional view taken along line 2—2 of Fig. 1.

Referring to the drawing, and particularly to the dominant features of the invention, my design comprises a handkerchief ornamented with a lace trimming A in the form of a flap forming a pocket between the handkerchief and the trimming for receiving a powder puff or the like article to show through the lace trimming.

I claim:

The ornamental design for a handkerchief or similar article, substantially as shown and described.

Dated, September 27, 1932.

EMIL METZGER.
